UNITED STATES PATENT OFFICE.

ROBERT H. GIESON, OF CARBON, ALBERTA, CANADA.

PUMP PIPE LIFT.

Application filed December 13, 1920. Serial No. 430,235.

To all whom it may concern:

Be it known that I, ROBERT HENRY GIESON, of the village of Carbon, in the Province of Alberta, Canada, have invented certain new and useful Improvements in Pump Pipe Lifts, of which the following is the specification.

My invention relates to improvements in pump pipe lifts and the object of the invention is to devise a pipe lift that will be free to slide down the pipe in a well and which can be so actuated at any particular point as to grip the pipe and lift the same from the well. A further object is to construct a pump-lift that will be capable of being readily and quickly attached to, and detached from the pipe.

My invention consists of a device constructed and arranged all as hereinafter more particularly described and illustrated in the accompanying drawing in which:

Fig. 1 represents a side elevation of a device constructed according to my invention showing the same applied to the pipe.

Fig. 2 is an elevation of the same taken at right angles to Fig. 1, and

Fig. 3 is a plan view.

Like characters of reference indicate corresponding parts in the different views.

1 is the pipe, 2 is a convexed member having a concaved interior 3 provided with suitable serrations 4. 5 and 6 are suitably spaced upper and lower lugs extending laterally from each side of the convexed member. 7 are vertical bolts, each extending through a pair of lugs 5 and 6 and provided at its lower end with a nut 8. 9 is a lever member having the concaved interior 10 provided with suitable serrations 11. 12 are trunnions extending laterally from the member 9 intermediately of the length of the same and provided with the pins 13 extending vertically therethrough.

14 are links pivotally connected to the respective lugs 5 and 6 by the bolts 7, the free ends carrying the rings 15 which are adapted to extend over the trunnions 12. 16 is a hook suitably connected to a cable 17, said hook adapted to engage a ring 18 on the lower end of the lever member 9.

The operation of the device is as follows:

The device is applied to the pipe at the top of the well by hooking the rings 15 of the links 14 over the trunnions 12, said rings being normally held thereon by the pins 13,

thus the member 2 is held on one side of the pipe and the member 9 on the other side. If force is exerted on the free end of the lever 9 it will be seen that the members 2 and 9 will be practically free on the pipe and will be permitted to slide down the same under the force of gravity.

When the device has reached the desired point it is merely necessary to pull on the cable 17 which will, through the medium of the hook 16 and the ring 18, pull up the free end of the lever member 9, thus drawing the member 2 inwardly and causing the serrations 4 to engage the pipe. Simultaneously the serrations 11 of the member 9 engages the other side of the pipe and consequently as long as the cable 17 is pulled upwardly the pipe 1 will be tightly held between such members 2 and 9 and can be pulled up from the well.

From the above description it will be apparent that I have devised a simple and effective pump pipe lift and one that can be readily and quickly applied to the pipe. Further a device constructed according to my invention can be manufactured very cheaply.

What I claim as my invention is:

1. In a pump pipe lift, a convexed member having a serrated concaved interior for application to one side of a pipe, a lever member having a serrated concaved interior for application to the other side of the pipe, links pivotally connected to the convexed member, laterally extending trunnions on the lever member, rings on the free ends of the links adapted to extend over the trunnions, pins extending through the trunnions for normally holding the rings thereon and means connected with the free end of the lever member for pulling the same in a forward direction.

2. A device of the character described, comprising coacting gripping members, a pair of spaced superposed lugs projecting outwardly from each of opposite sides of one of said members, a pin extending between the lugs of each pair and links connected between said pins and the remaining gripping member.

3. A device according to claim 2, wherein the said pins are detachably secured to the lugs with which they are associated.

4. A device according to claim 2, in which each of said pins is in the form of a bolt

having a head at one end for engaging one lug and a nut at the opposite end for engaging the remaining lug.

5. A device of the character described, comprising coacting gripping members, trunnions carried by one of said members, links carried by the remaining member, rings secured to said links adapted to receive the trunnions therethrough and means 10 for retaining the trunnions and rings in assembled relation.

6. A device of the character described, comprising coacting gripping members, trunnions carried by one member and rings carried by the other member for receiving the 15 trunnions therethrough.

7. A device of the character described, comprising coacting gripping members, pro-

vided with opposing gripping surfaces, one of said members being formed with an integral lever extension extending outwardly and downwardly with respect to the gripping surface thereof, means pivotally connecting the lever extension to the other member and hoisting means connected to the lower end 20 of said extension, in which the means for connecting the members together comprises trunnions carried by the lever extension of one member, rings receiving the trunnions therethrough and means connecting the rings 25 to the remaining member.
